United States Patent Office

Des. 220,887
Patented June 8, 1971

220,887

DUPLICATING MACHINE

Wallace A. Monson, Golden Valley, Minn., assignor to
Minnesota Mining and Manufacturing Company, St.
Paul, Minn.

Filed Feb. 18, 1970, Ser. No. 21,479

Term of patent 14 years

Int. Cl. D16—05

U.S. Cl. D61—1

FIG. 1

FIG. 2

FIG. 3

FIG. 4

FIG. 5

FIG. 6

FIG. 1 is a perspective view of a duplicating machine showing my new design;

FIG. 2 is a front elevational view thereof;

FIG. 3 is a right side elevational view, the opposite side being a mirror image thereof;

FIG. 4 is a rear elevational view; and

FIG. 5 is a bottom plan view.

I claim:

The ornamental design for a duplicating machine, substantially as shown and described.
